UNITED STATES PATENT OFFICE.

THOMAS E. BARNUM, OF MILWAUKEE, WISCONSIN, ASSIGNOR TO THE CUTLER-HAMMER MFG. CO., OF MILWAUKEE, WISCONSIN, A CORPORATION OF WISCONSIN.

MOTOR-CONTROLLER.

1,301,088.

Specification of Letters Patent. Patented Apr. 22, 1919.

Application filed January 12, 1915. Serial No. 1,756.

To all whom it may concern:

Be it known that I, THOMAS E. BARNUM, a citizen of the United States, residing at Milwaukee, in the county of Milwaukee and 5 State of Wisconsin, have invented new and useful Improvements in Motor-Controllers, of which the following is a full, clear, concise, and exact description, reference being had to the accompanying drawing, forming 10 a part of this specification.

This invention relates to controllers for electric motors and more particularly to self starters therefor.

One object of the invention is to provide 15 a self starter for elevator, printing press and other service where quick response of the starter is desired.

Other objects and advantages of the invention will hereinafter appear.

20 The accompanying drawings illustrate one embodiment of the invention which will now be described.

In the drawings,

25 Figure 1 is a front elevation of the controller;

Fig. 2 is an end elevation looking from the left hand side of Fig. 1;

Fig. 3 is a sectional view on line 3—3, Fig. 1 and

30 Fig. 4 is a diagrammatic view of one circuit arrangement for the controller.

As illustrated in Figs. 1 to 3, the controller includes an electro-responsive main switch 1, a multi-switch accelerating device 2 tending to move to running position, a solenoid 3 for restoring said accelerating device to starting position, and a mechanical latching device 4 (Fig. 2) for holding the accelerating device in starting position

40 subject to release by said main switch.

Also, the controller includes interconnections between the two electro-responsive devices whereby the accelerating device is restored to starting position whenever the

45 main switch is opened and whereby the main switch is insured against response except when the accelerating device is in starting position. It will thus be observed that the controller may be operated to start and

50 accelerate the controlled motor immediately upon closure of the energizing circuit of the main switch and that the motor is insured due protection upon closure of the main switch. Hence the advantage of the controller in elevator and printing press service,

where quick starting is desired, will be readily apparent.

The main switch 1 as illustrated is of conventional form and briefly described includes two contact arms 5 and 6 mounted upon but insulated from the armature 7 of an electromagnet 8 supported in a suitable frame 9 fixed to an insulating panel 10. As illustrated in Fig. 3 the armature 7 is fulcrumed on a pin 11 and the arms 5 and 6 have pivoted contact members 12 coöperating with fixed contacts 13 inclosed in suitable blowout devices 14. Also, referring to Fig. 1, the armature 7 has two downward extensions 15 carrying a cross-bar 16 coöperating with two pairs of yielding contact fingers 17 and 18 mounted on the panel 10, the bar 16 being suitably insulated from said armature. The arrangement is such that when the main switch is in open position bar 16 bridges contact fingers 17 whereas when said switch closes, bar 16 leaves fingers 17 and bridges fingers 18. The left hand extension 15 of the armature also carries a pin 19 to trip the latch of the accelerating device, as hereinafter set forth.

55 The accelerating device includes a plurality of contact fingers 20 of conventional form coöperating with contacts 21 on the panel 10. The several contact fingers are mounted upon a common rotatable shaft or bar 22 having end bearings 23 and 24 and each finger has a trunnion bearing 25 on said shaft. Also, each contact finger has projecting therethrough a pin 26 fixed at one end to a plate 27 on the panel 10 and carrying at its outer end a coil spring 28 bearing against said finger to press the same inwardly. The springs 28 thus tend to move the contact fingers into engagement with the contacts 21, thereby tending to move the device to running position, as above set forth. The shaft 22, on the other hand, has a series of cams 29 (Fig. 3) which upon counter-clockwise rotation of said shaft progressively lift the fingers out of engagement with the contacts 21 and upon clockwise rotation restrain the contact fingers for progressive engagement with the contacts 21. Counter-clockwise rotation of the shaft 22 is effected by the solenoid 3 which is mounted in a frame 30 fixed to the panel and provided with a plunger 31 connected to the extremity of an arm 33 fixed to and projecting outwardly from the shaft 22. 110

The clockwise rotation of the shaft is effected jointly by the tension of the springs 28 and a weight 34 on the arm 33 against the action of a dash-pot 35 mounted on the 5 solenoid frame and connected to the extremity of the arm 33 (Fig. 2). As will be understood, the dash-pot is provided to retard the movement of the accelerating device for insuring gradual acceleration. Also, 10 the accelerating device is provided with an adjustable stop to vary its limit of downward movement to vary the degree of acceleration effected thereby. This stop comprises a lever 36 pivoted concentrically with 15 the lever 33 and having at its inner end an offset lug 37 to abut an extension 38 of the solenoid frame, while at its opposite end it is provided with an adjustable connection with the arm 33. This adjustable connection 20 includes a pin 39 at the free end of the stop lever and a segment 40 on the arm 33 having a series of notches or recesses therein to receive the pin 39. As shown, the arm 33 and stop lever are in alignment 25 whereby the accelerating device is permitted a maximum downward movement, whereas the downward movement may be restricted by lowering the free end of the stop lever relative to the arm 33 and locking 30 said lever and arm together in the desired relation according to the degree of restriction desired.

The latching means for the accelerating device includes a pivoted hook 41 (Fig. 2) suspended from a suitable bracket 42 and biased by a spring 43 to engage a lug 44 on the arm 33 in starting position of the accelerating device. This provides for automatic latching of the accelerating device in starting 35 position and release of the accelerating device is effected by the pin 19 on the main switch acting upon an extension 45 of the hook 41. As will be apparent from Fig. 2 the hook moves in a counter-clockwise direction to latch the accelerating device, whereas the pin 19 which moves outwardly upon closure of the main switch, acts upon the extension 45 to move the hook in a clockwise direction to release the accelerating device. 40 Also, as will be apparent from Fig. 2, when the accelerating device is released the lug 44 engages the hook 41 to prevent return or counter-clockwise movement of said hook until return of the accelerating device to 45 starting position, for a purpose hereinafter set forth.

The aforesaid interconnections of the two electro-responsive devices are effected by the above-described contacts associated with the 50 main switch and by two additional sets of contact fingers 46 and 47. The contacts 46 are of the same form as contacts 17 and 18 and are adapted to be bridged by a pin 48 (Fig. 1) carried by an extension 49 of the 55 latching hook 44 (Fig. 2). The arrange-

ment is such that fingers 46 are bridged by the pin 48 upon tripping of the latch and in consequence upon release of the accelerating device, whereas they are disengaged by said pin upon movement of the latching hook to 70 latching position. As before stated, the hook 41 when tripped is held against return or counter-clockwise movement until return of the accelerating device to starting position and the pin 48 is thereby held independently of the main switch, in bridging engagement with the contacts 46 pending full return of the accelerating device to starting position. The contact fingers 47 are similar to fingers 46 and are adapted to 75 be bridged by a pin 50 (Fig. 1) carried by a downwardly extending lug 51 on the arm 33 of the accelerating device (Fig. 2). The arrangement is such that in down position of said arm the pin 50 is disengaged from 80 fingers 47 whereas upon upward movement of said arm, said pin is moved to bridge said fingers. As will be hereinafter more fully described the contacts 46-48 coöperate with contacts 16-17 to energize solenoid 3 85 when main switch 1 is opened and the accelerating device is in running position. On the other hand, contacts 46-48 serve to interrupt the circuit of solenoid 3 upon return of the accelerating device to starting position, while contacts 16-17 serve to interrupt the energizing circuit of solenoid 3 when the main switch closes. Contacts 47-50 are included in the energizing circuit of the main switch and open said circuit upon 100 movement of the accelerating device from starting position thereby insuring against energization of the main switch except in starting position of the accelerating device, while contacts 16-18 complete a maintaining circuit for the main switch after response thereof.

Referring now to Fig. 4 the controller is shown schematically and as governing an alternating current motor M. The main 110 switch 1 controls the continuity of the primary circuit of the motor while the accelerating device controls resistances R, R' and R² in the secondary circuit of the motor, said device serving to exclude said resistances 115 in steps. For purposes of illustration the motor M has been shown as of a three-phase type, being supplied with current from lines 52-53 and 54 while the winding of the main switch and the solenoid 3 are connected 120 across one phase of the supply circuit, the main switch being governed by a suitable control switch 55. With the devices positioned as illustrated the motor is disconnected from circuit and the windings of 125 both the main switch and accelerating device deenergized.

Assuming now that switch 55 be closed, circuit will be established from line 52 through switch 55, by conducting 56 through 130

contacts 47—50, by conductor 57 through the winding of main switch 1, by conductor 58 to line 53. This energizes main switch 1 causing the same to complete the primary circuit of the motor, which circuit is obvious and needs no description, and also to trip the latch of the accelerating device. The accelerating device then operates to accelerate the motor by excluding the resistances R, 5 R' and R'' through circuit variations which are so obvious as to require no description. Main switch 1 upon closing also completes a maintaining circuit for itself extending from switch 55 by conductor 59 through contacts 16—18, by conductor 60 to conductor 57, thereby paralleling the contacts 47—50 associated with the accelerating device.

Assume now that the motor has been started and fully accelerated and that it is desired to stop the same. This is accomplished by opening switch 55 to deenergize the main switch 1. The main switch thereupon opens completing the circuit of solenoid 3 from line 52 by conductor 61 through said solenoid, by conductor 62 through contacts 46—48, by conductor 63 through contacts 16—17, by conductor 64 to line 53. Solenoid 3 thereupon responds to restore the accelerating device to starting position and upon full return movement of the accelerating device the latching device thereof sets and in so doing disengages contact 48 from contact 46. This deenergizes solenoid 3 leaving the accelerating device restrained solely by the mechanical latching means and subject to release for immediate operation upon reclosure of the main switch.

Should the main switch open through failure of voltage the result would be the same as that described in that the accelerating device would be restored to starting position upon restoration of voltage and the main switch would be insured against reclosing pending such return movement of the accelerating device.

It will, of course, be understood that the invention may be embodied in other forms falling within the scope of the appended claims.

50 What I claim as new and desire to secure by Letters Patent is:

1. In a motor controller, in combination, an electro-responsive power controlling device, a separately operable accelerating device biased to running position, a device for holding said accelerating device in starting position, means acting upon said last mentioned device to release said accelerating device upon operation of said power controlling device, and means to directly control said power controlling device for starting of the controlled motor.

2. In a motor controller, in combination, an electro-responsive power controlling device, an accelerating device biased to run-

ning position, a latching device for holding said accelerating device in starting position, means acting upon said latching device to release said accelerating device upon operation of said power controlling device and 70 electro-responsive means for returning said accelerating device to starting position upon return of said power controlling device to initial position.

3. In a motor controller, in combination, 75 an electro-responsive power controlling device, an accelerating device biased to running position, a latching device for holding said accelerating device in starting position, means associated with said power controlling device to trip said latching device upon establishment of power connections for the motor, electro-responsive means for restoring said accelerating device to starting position upon operation of said power controlling device to interrupt power connections and means associated with said latching device to deenergize said electro-responsive means upon restoration of said accelerating device to starting position.

4. In a motor controller, in combination, means controlling the continuity of the motor circuit, a separately operable accelerating device biased to running position, means normally holding said device in starting position subject to release by the former means when operated to close the motor circuit, and means for automatically returning said device from running position to starting position upon opening of the motor circuit by the first mentioned means.

5. In a motor controller, in combination, power actuated means controlling the continuity of the motor circuit, an accelerating device biased to running position, means normally holding said device in starting position subject to release by the former means when operated to close the motor circuit, means for automatically returning said device from running position to starting position upon opening of the motor circuit by said former means and means for rendering return of said accelerating device to starting position prerequisite to operation of the first mentioned means to close the motor circuit.

6. In a motor controller, in combination, a main switch controlling the continuity of the motor circuit, an accelerating device tending to move from starting position to running position and having electro-responsive means controlled by said switch to move the same to starting position upon interruption of the motor circuit and means controlled by said switch for retaining said device in starting position subject to release upon operation of said first mentioned means to close the motor circuit.

7. In a motor controller, in combination, means controlling the continuity of the

- motor circuit, accelerating means tending to move from starting position to running position and having releasable mechanical means for retaining the same in starting position subject to release by said former means and electro-responsive means controlled by said first mentioned means to return said accelerating means to starting position upon interruption of the motor circuit and self-controlled to effect its own de-energization upon the aforesaid operation of said accelerating means.
8. In a motor controller, in combination, means controlling the continuity of the motor circuit, accelerating means tending to move from starting position to running position, electro-responsive means controlled by said first mentioned means to return said accelerating means to starting position upon interruption of the motor circuit and having associated therewith means to effect its deenergization upon such operation of said accelerating means, and other means to retain said accelerating means in starting position subject to automatic release upon reclosure of the motor circuit.
9. In a motor controller, in combination, means controlling the continuity of the motor circuit, accelerating means tending to move from starting position to running position, electro-responsive means responsive to return said accelerating means to starting position upon interruption of the motor circuit by said first mentioned means subject to release upon subsequent operation of said first mentioned means to reclose the motor circuit.
10. In a motor controller, in combination, means controlling the continuity of the motor circuit, accelerating means normally locked in starting position and subject to release by said first mentioned means upon closing the motor circuit, said accelerating means when so released automatically moving to running position, and electro-responsive means controlled by said first mentioned means to return said accelerating means to starting position upon interruption of the motor circuit.
11. In a motor controller, in combination, means controlling the continuity of the motor circuit, accelerating means normally locked in starting position and subject to release by said first mentioned means upon closing the motor circuit, said accelerating

means when so released automatically moving to running position, and electro-responsive means controlled by said first mentioned means to return said accelerating means to starting position upon interruption of the motor circuit, said last mentioned means having associated therewith means to de-energize the same upon return of said accelerating means to starting position.

12. In a motor controller, in combination, electro-responsive means controlling the continuity of the motor circuit, a control switch therefor, accelerating means tending to stand in running position and having electro-responsive means for moving the same to starting position and interconnections between said means whereby the energization of said accelerating means is effected by said first mentioned means upon interruption of the motor circuit and whereby return of said accelerating means establishes connections for energization of said first mentioned means by said control switch.

13. In a motor controller, in combination, an electro-responsive main switch, accelerating means tending to stand in running position and having means to lock the same in starting position subject to release by said main switch, electro-responsive means for returning said accelerating means to starting position, a switch in the energizing circuit of said main switch associated with said accelerating means to insure against closure of said circuit except when said accelerating means is in starting position, a switch in the energizing circuit of said second-mentioned electro-responsive means associated with said main switch to be closed thereby when said main switch is moved to interrupt the motor circuit and to be opened thereby when said main switch is moved to close the motor circuit, and a second switch in the energizing circuit of said second-mentioned electro-responsive means operable automatically to interrupt said circuit upon return of said accelerating means to starting position.

In witness whereof, I have hereunto subscribed my name in the presence of two witnesses.

THOMAS E. BARNUM.
